DEVICE FOR WRAPPING HOLLOW
PACKAGESHenry J. McDermott, Collingdale, Pa., assignor
to American Viscose Corporation, Wilmington,
Del., a corporation of Delaware

Application July 23, 1946, Serial No. 685,745

13 Claims. (Cl. 226—2)

1

This invention relates to modifications of a form of apparatus shown in my copending application Serial No. 568,462, filed December 16, 1944, now Patent No. 2,436,481, for applying a covering member to a hollow package.

The present invention is particularly useful for the application of a flexible protective covering member such as a knitted sleeve or even a paper sleeve to a hollow package of artificial filaments, such as a cake of rayon obtained by collection in a spinning pot.

The present invention has as its principal object the provision of a simplified form of apparatus which is highly convenient to operate. Additional objects and advantages of the invention will be apparent from the drawing and the description thereof hereinafter.

In the drawing, which is illustrative of the invention—

Figure 1 is an elevation in cross-section of a preferred embodiment.

Figure 1a is a perspective view of the package-receiving bucket and package-engaging plate of Figure 1 with other parts generally removed.

Figure 2 is an elevation in cross-section of a modification, and

Figure 3 is a view taken on line III—III of Figure 2 showing a latching construction.

In general, the device of the present invention comprises two concentric hollowed structures and a package-engaging or package-supporting member or plate adapted to fit between the two concentric structures. Relative movement is imparted to the package-engaging member and at least the outer of the concentric structures and advantageously, spring means normally urges the relative displacement of the member and outer structures to a condition in which the package-engaging member is near the open end of the outer structure. Advantageously, latching means may be provided to retain the various parts in that relative position in which the package-engaging member is well within the recess formed within the hollowed-out outer structure.

As shown in Figures 1 and 1a, the device comprises suitable supporting means in the form of a hollow post 2 secured to the floor or other base by means of a flange 3. To the upper end of the post there is secured a bucket-shaped structure 4 having an upwardly extending sleeve-like portion 5 with a hollow interior. Concentrically within the sleeve of the bucket structure 4 there is disposed an inner structure comprising a cup-shaped element 6 having a recess 7 adapted to receive one end of a flexible wrapping member

2

8. The concentric structures are open at the upper ends and in the recess between the sleeves of the inner and outer structures, a plate 9 for engaging one end of the package (and, when the device is in the vertical position shown, for supporting the package) is carried, such as by means of a plurality of rods 10. These rods 10 extend slidably through openings 11 in the outer structure and are turned inwardly to a supporting block or hub 12 carried upon a hollow shaft 13 and slidable within the hollow post 2. A spring 14 normally urges the member 9 into the position shown in Figure 1, a central rod 15 within the spring tending to guide the spring into the hollow shaft 13. A collar 16 secured to the shaft 13 has a projection 17 extending through an axial slot 18 in the lower end of the post 2. The projection 17 serves as a foot lever to facilitate the manipulation of the device. Adjacent the lower end of the slot 18, a latch 19 is provided (see Figure 3). This latch is counterweighted at 19a so that it normally rests in the position shown, the cam surface 19b serving to be engaged by the foot lever 17 so that such lever can pass into the latching position shown in Figure 3, and this latch may be rocked out of locking position over the projection 17 as shown in Figure 3 by means of the foot crank lever 20 whose pivotal shaft 21 extends through a bearing in a block 22 to a point of securing with the latch 19.

In operating the embodiment of Figures 1 and 1a, a flexible sleeve-like cover 8 is placed upon the upper end of the device as shown in Figure 1 with one end of the sleeve tucked within the recess 7 of the cup-like element 6 and with the other end of the cover turned back over the outer sleeve 5. The hollow package P, such as a wound cake of rayon, is then placed upon the portion of the cover resting over the member 9. The operator then presses the package downwardly with the palms of his hands until he can engage the projection 17 with the latch 19, this corresponding preferably to a condition in which the package is completely withdrawn into the recess between the inner and outer structures. During such downward movement of the package, the covering 8 is applied to both inside and outside surfaces of the hollow package. At the conclusion of the downward movement of the package, it is only necessary for the operator to withdraw the remainder of the end of the cover tucked within the recess 7 and extend it over the top end of the package and partly over the upper end of the outer sleeve 5. Preferably, sufficient of one end of the cover is tucked into the

3

cup-like element 6 so that at the final step the cover overlaps the upper portion of the outer surface of the outer periphery of the package as well as the top end surface and so that the other end of the cover previously disposed outside the outer structure is insufficient to reach the top of the package. This assures that the cover will not pull away from the top end surface of the package.

The package may then be ejected from the sleeve 5 and this may be accomplished either by releasing the projection 17 from the latch 19 so that the spring 14 lifts the package upwardly or by the insertion of the fingers through the axially directed slots 23 in sleeve 5 and radial slots 23a in the plate 9 and then lifting the package with the fingers. See Figure 1a especially. While slots 23 may extend clear through the upper rim of the bucket 5, it is preferable to avoid the break in the rim by terminating the upper ends of the slots as shown in Figure 1a so that a smooth rim is provided for engaging the cover or wrapper. When the slots extend through the upper rims of sleeve 5, their lower ends may reach only part way to the bottom of the sleeve 5 and the element 6 may be provided with aligned slots of the same length (as shown in Figure 2) to permit seizing of the package by fingers reaching through the slots around the upper end of the package. Preferably, however, the slots extend to the bottom of sleeve 5 and partway inward along the bottom (as shown in Figures 1 and 1a) in alignment with slots 23a in the plate 9.

As the package moves upwardly during ejection, the portion of the wrapper covering the top end of the package and extending over the upper end of sleeve 5 slides off the sleeve 5 and grips the upper end of the outer periphery of the package, overlapping the other end of the cover previously applied during the downward movement of the package into the recess within the sleeve 5.

Figure 2 illustrates a modification in which such of the parts as correspond substantially to the parts in Figure 1 are given corresponding numbers. The supporting post 2 secured to a floor or other base by means of a flange 3 carries in relative fixed relationship thereto the bucket-like structure 4 having the outer sleeve 5 in which notches or slots 23b may be provided if desired. A shaft 24 is axially slidable within a bore through the central hub of the bucket-like structure 4 and carries at its upper end the package-engaging member 9a which in this instance is a plate having an outer free annular portion adapted to receive the end of the cake. To the top of the plate is secured the cup-like or sleeve-like inner structure 6 having the hollow recess 7 adapted to receive one end of the cover 8. The structure 6 may have notches or slots 23c aligned with slots 23b and extending to approximately the same depth from the upper rim of the structure 6 as slots 23b do from the upper rim of sleeve 5. If desired these slots may be replaced by the slot system 23 and 23a of Figures 1 and 1a.

The shaft 24 is secured to an intermediate sliding block 25 from which depends the hollow shaft 13 containing the spring 14 and carrying the collar 16 with its projecting member 17. A rod 15 is provided as in Figure 1 and the latching system comprising latch 19 and crank lever 20 is identical to that shown in Figure 1.

In this embodiment, the member 9a is initially in an upper position adjacent the open end of the sleeve 5. The cover 8 is placed about

4

the inner structure 6 with a portion of one end tucked into the recess 7 and the other end being overlapped about the sleeve 5. The cake is inserted over the cover carried by the inner concentric structure 6 and brought to rest upon the portion of the cover carried by the annular free portion of the member 9a. Then the package is moved downwardly into the recess within the sleeve 5, such movement sliding the outer end of the cover from about the sleeve 5 into engagement with the outer periphery of the package. The position thus reached is shown in Figure 2 and it is only necessary for the operator to withdraw the end of the cover tucked in recess 7 and spread it over the top end of the outer structure and thereafter to remove the package from the outer structure. This removal may be accomplished either by insertion of the fingers through notches 23 and lifting the cake from the member 9a or by releasing the projection 17 from latch 19 and allowing the spring 14 to lift the inside assembly with the package to its upper position.

Both embodiments shown and described herein are adapted to rapid manipulation. The fatigue of the operators is greatly reduced by the provision of the spring means 14, which eliminates the lifting of the package-supporting structure. Of the two embodiments, Figure 1 is preferred, since it is somewhat easier for an operator to place the package in position without mussing up the internal windings which may occur if insufficient care is taken in placing a package about the inner structure 6 of Figure 2.

It is to be understood that changes and variations may be made without departing from the spirit and scope of the present invention as defined in the appended claims.

I claim:

1. An apparatus for applying a cover to a hollow package comprising supporting means, two concentric at least partially hollow, rigid structures, each having a cylindrical wall concentric with that of the other, both of the structures being carried by the supporting means and being held in relatively fixed position thereby, each of said structures being open at least at one end adjacent the open end of the other structure, a package-engaging member disposed in the open recess thus provided between the concentric walls, the mounting arrangement of the member on the one hand and the two concentric structures on the other hand being such as to permit relative motion therebetween in an axial direction from a position in which the member is near the open end of the recess between the two walls to a position in which it is well within said recess.

2. An apparatus for applying a cover to a hollow package comprising supporting means, two concentric at least partially hollow, rigid structures, each having a cylindrical wall concentric with that of the other, both of the structures being carried by the supporting means and being held in relatively fixed position thereby, each of said structures being open at least at one end adjacent the open end of the other structure, a package-engaging member disposed in the open recess thus provided between the concentric walls, the mounting arrangement of the member on the one hand and the two concentric structures on the other hand being such as to permit relative motion therebetween in an axial direction from a position in which the member is near the open end of the recess between the two walls to a position in which the member is well within said recess.

tion in which it is well within said recess, and spring means connected with the member and normally urging the member to the position near the open end of the recess in the outer structure.

3. An apparatus for applying a cover to a hollow package comprising supporting means, two concentric at least partially hollow, rigid structures, each having a cylindrical wall concentric with that of the other, both of the structures being carried by the supporting means, each of said structures being open at least at one end adjacent the open end of the other structure, a package-engaging member disposed in the open recess thus provided between the concentric walls, the mounting arrangement of the member and the other structure being such as to permit relative motion therebetween in an axial direction from a position in which the member is near the open end of the recess to a position in which it is well within the recess, spring means connected with the member and normally urging the member to the position near the open end of the recess, and slots in the outer cylindrical wall extending generally parallel to the axis.

4. An apparatus for applying a cover to a hollow package comprising supporting means, two concentric at least partially hollow, rigid structures, each having a cylindrical wall concentric with that of the other, both of the structures being carried by the supporting means, each of said structures being open at least at one end adjacent the open end of the other structure, a package-engaging member disposed in the open recess thus provided between the concentric walls, the mounting arrangement of the member and the other structure being such as to permit relative motion therebetween in an axial direction from a position in which the member is near the open end of the recess to a position in which it is well within the recess, slots in the outer cylindrical wall extending generally parallel to the axis of the walls, and spring means connected with the member and normally urging the member to the position near the open end of the recess.

5. An apparatus for applying a cover to a hollow package comprising supporting means, two concentric at least partially hollow, rigid structures, each having a cylindrical wall concentric with that of the other, both of the structures being carried by the supporting means, each of said structures being open at least at one end adjacent the open end of the other structure, a package-engaging member disposed in the open recess thus provided between the concentric walls, the mounting arrangement of the member and the other structure being such as to permit relative motion therebetween in an axial direction from a position in which the member is near the open end of the recess to a position in which it is well within the recess, slots in the outer cylindrical wall extending generally parallel to the axis of the walls, aligned slots in the inner wall, and spring means connected with the member and normally urging the member to the position near the open end of the recess.

6. An apparatus for applying a cover to a hollow package comprising supporting means, two concentric at least partially hollow, rigid structures, each having a cylindrical wall concentric with that of the other, both of the structures being carried by the supporting means, each of said structures being open at least at one end adjacent the open end of the other structure, a package-engaging member disposed in the open

recess thus provided between the concentric walls, means for displacing the member in an axial direction from a position in which the member is near the open end of the recess to a position in which it is well within the recess, slots in the outer cylindrical wall extending generally parallel to the axis of the walls to a depth corresponding to the depth of displacement of the package-engaging member within the recess, aligned slots in the outer portion of the package-engaging member, and spring means connected with the member and normally urging the member to the position near the open end of the recess.

15 7. An apparatus for applying a cover to a hollow package comprising supporting means, two concentric at least partially hollow, rigid structures, each having a cylindrical wall concentric with that of the other, both of the structures being carried by the supporting means, the outer structure being held in relatively fixed position thereby, each of said structures being open at least at one end adjacent the open end of the other structure, a package-engaging member disposed in the open recess thus provided between the concentric walls, means for displacing the member in an axial direction from a position in which the member is near the open end of the recess to a position in which it is well within the recess, slots in the outer cylindrical wall extending generally parallel to the axis of the walls to a depth corresponding to the depth of displacement of the package-engaging member within the recess, aligned slots in the outer portion of the package-engaging member, and spring means connected with the member and normally urging the member to the position near the open end of the recess.

30 8. An apparatus for applying a cover to a hollow package comprising supporting means, two concentric at least partially hollow, rigid structures, each having a cylindrical wall concentric with that of the other, both of the structures being carried by the supporting means and being held in relatively fixed position thereby, each of said structures being open at least at one end adjacent the open end of the other structure, a package-engaging member disposed in the open recess thus provided between the concentric walls, the mounting arrangement of the member on the one hand and the two concentric structures on the other hand being such as to permit relative motion therebetween in an axial direction from a position in which the member is near the open end of the recess to a position in which it is well within the recess, slots in the outer cylindrical wall extending generally parallel to the axis of the walls to a depth corresponding to the depth of displacement of the package-engaging member within the recess, aligned slots in the outer portion of the package-engaging member, and spring means connected with the member and normally urging the member to the position near the open end of the recess.

35 9. An apparatus for applying a cover to a hollow package comprising supporting means, two concentric at least partially hollow, rigid structures, each having a cylindrical wall concentric with that of the other, both of the structures being carried by the supporting means, each of said structures being open at least at one end adjacent the open end of the other structure, a package-engaging member disposed in the open recess thus provided between the concentric walls, the mounting arrangement of the member and the

other structure being such as to permit relative motion therebetween in an axial direction from a position in which the member is near the open end of the recess to a position in which it is well within the recess, slots in the sleeve extending generally parallel to the axis of the walls to a depth corresponding to the depth of displacement of the package-engaging member within the recess, aligned slots in the outer portion of the package-engaging member, spring means connected with the member and normally urging the member to the position near the open end of the recess, and latch means connected with the member for retaining the member in its position well within the recess against the normal action of the spring.

10. An apparatus for applying a cover to a hollow package comprising supporting means, two concentric at least partially hollow, rigid structures, each having a cylindrical wall concentric with that of the other, both of the structures being carried by the supporting means and being held in relatively fixed position thereby, each of said structures being open at least at one end adjacent the open end of the other structure, a package-engaging member disposed in the open recess thus provided between the concentric walls, the mounting arrangement of the member on the one hand and the two concentric structures on the other hand being such as to permit relative motion therebetween in an axial direction from a position in which the member is near the open end of the recess to a position in which it is well within the recess, slots in the outer cylindrical wall extending generally parallel to the axis of the walls to a depth corresponding to the depth of displacement of the package-engaging member within the recess, aligned slots in the outer portion of the package-engaging member, spring means connected with the member and normally urging the member to the position near the open end of the recess, and latch means connected with the member for retaining the member in its position well within the recess against the normal action of the spring.

11. An apparatus for inserting an annular fibrous mass into a cover comprising supporting means, two concentric at least partially hollow, rigid structures, each having a cylindrical wall

5 concentric with that of the other, both of the structures being carried by the supporting means and being held in relatively fixed position thereby, each of said structures being open at least at one end adjacent the open end of the other structure, an annular member disposed in the open recess thus provided between the concentric walls, the mounting arrangement of the member on the one hand and the two concentric structures on the other hand being such as to permit relative motion therebetween in an axial direction from a position in which the member is near the open end of the recess between the two walls to a position in which it is well within the recess.

12. An apparatus for inserting an annular fibrous mass into a cover comprising supporting means, two concentric cylinders carried by the supporting means and held in relatively fixed position thereby, each of said cylinders being open at least at one end adjacent the open end of the other cylinder, an annular member disposed in the open recess thus provided between the cylinders, means for moving the member in an axial direction between a position in which the member is near the open end of the recess and a position in which it is well within the recess.

13. Apparatus for inserting an annular mass into a cover comprising supporting means, two concentric cylinders extending vertically upwardly from the supporting means, said cylinders being open at their upper ends and being held in relatively fixed position by the supporting means, an annular member disposed in the open recess between the cylinders, and means for moving the member up and down axially of the cylinders between a position in which the member is near the open end of the recess in the position in which it is well within the recess.
